United States Patent Office

Des. 181,892
Patented Jan. 7, 1958

181,892

JAR FOR FOOD

Sol Young, New York, N. Y., assignor to L. Batlin & Son, Inc., New York, N. Y., a corporation of New York

Application October 15, 1956, Serial No. 43,352

Term of patent 3½ years

(Cl. D58—25)

Fig. 1 is a front view of a jar for food embodying my new design;

Fig. 2 is a top view thereof;

Fig. 3 is a side view thereof; and

Fig. 4 is a rear view thereof.

I claim:

The ornamental design for a jar for food, as shown.
